US00D626440S

(12) **United States Design Patent**
Daicos

(10) **Patent No.:** **US D626,440 S**
(45) **Date of Patent:** **** Nov. 2, 2010**

(54) **HAND-HELD SPORTS STATISTICS
COUNTER**

(75) Inventor: **Peter Daicos**, Victoria (AU)

(73) Assignee: **Sportzstats Pty Ltd**, Victoria (AU)

(**) Term: **14 Years**

(21) Appl. No.: **29/339,765**

(22) Filed: **Jul. 7, 2009**

Related U.S. Application Data

(62) Division of application No. 29/281,850, filed on Jul. 3, 2007, now Pat. No. Des. 596,503.
